HARRY H. STOUT, OF NEW YORK, N. Y., ASSIGNOR TO GENERAL CHEMICAL COMPANY, OF NEW YORK, N. Y., A CORPORATION OF NEW YORK.

ROASTING OF SULFUR-BEARING ORES.

1,181,183.

Specification of Letters Patent.

Patented May 2, 1916.

Application filed July 31, 1914. Serial No. 854,230.

To all whom it may concern:

Be it known that I, HARRY H. STOUT, a citizen of the United States, and a resident of the borough of Manhattan, city, county, and State of New York, have invented certain new and useful Improvements in the Roasting of Sulfur-Bearing Ores, of which the following, taken in connection with the accompanying drawings, is a specification.

10 My invention relates to the roasting of sulfur-bearing ores, especially in connection with a rotary roasting furnace of the type shown in United States Letters Patent, No. 976,175 to John B. F. Herreshoff, dated November 22, 1910, and the object of my invention is to provide a regulatable distribution of heat, and controllable temperature conditions on each of the several roasting hearths or shelves of such a furnace. It has long been known that an obstacle to the most economical and efficient operation of furnaces of this type is the formation of incrustations which clog up the moving parts of the furnace, or of 25 "scars," *i. e.* fused masses of the material undergoing roasting, which attach themselves with more or less firmness to the hearth surface or to the rabble teeth or to both, thus bringing about inefficiencies in operation due to stoppage and due to the physical condition of the agglomerated material, which renders it incapable of being deprived of its sulfur content to the extent necessary for successful commercial operation. These scars or incrustations usually form in the upper hearth spaces the temperature of which is apt to be excessively high while the lower hearth spaces are at the same time at a temperature which is 35 usually too low for efficient operation. If, as has been proposed, the furnace is operated at below normal capacity, the formation of these agglomerated masses may to some extent be prevented, but such operation is obviously inefficient and is not capable of being controlled.

I have found that by a proper transfer of the heat generated on any hearth in excess of that heat necessary to bring about 50 satisfactory roasting, to some other hearth having insufficient heat or temperature conditions, satisfactory roasting can be effected, coupled with a capacity per day greater

than under the most favorable conditions heretofore obtaining; that by so operating 55 it is possible to have fewer interruptions than under the best practice heretofore obtaining, and fewer repair charges.

In order to make clear the nature of my invention and to explain fully the process 60 thereof I will now refer to the accompanying drawings in which is shown a roasting furnace by the use of which the process of my invention may be carried out, in which drawings—

Figure 1 shows the furnace in central vertical section, and Fig. 2 shows a plan view thereof, certain parts being in section.

The furnace illustrated comprises a number of superposed hearths 1 extending 70 inwardly from an outer, cylindrical wall 2 and providing roasting spaces between the hearths, which spaces are traversed by rabble or stirring arms 3, rotatably supported by a central, vertical double-walled shaft 75 4. Through the central passage of the shaft, air or other suitable cooling medium is forced, from which passage it passes through the several rabble arms in parallel and issues therefrom into the annular passage 80 of the shaft, which surrounds the central passage thereof.

In communication with the top of the annular channel of the shaft is a transverse conduit 5, the ends of which connect with 85 the bustle pipe 6, the latter being in the form of a ring of approximately the same diameter as the furnace itself and being supported upon the cylindrical wall 2 of the furnace. The bustle pipe communicates 90 with a plurality of vertical flues or conduits 7, preferably metallic, which are built into the wall 2, so that their inner walls are in direct contact with the products of roasting in the furnace hearth-spaces and which extend from the bustle pipe to the lowest hearth-space. Air or other fluid is thus capable of being conducted by the conduits 95 7 from the bustle pipe to the roasting space of the said lowest hearth. It will be understood, of course, that the conduits may discharge into other hearth spaces than the lowest one and that certain of them may discharge into the lowest space while others of them may discharge into other roasting 105 spaces. I have found, however, that suc-

cessful and efficient operation may be had in practice with a furnace in which all of the conduits 7 discharge into the lowermost roasting space.

5 An outlet into the atmosphere is provided in the form of a stack 8 which may extend upwardly from the transverse conduit 5 and is provided with a valve or damper *a*. A pipe 9 insulated from the 10 heat of the furnace, or a plurality of such 15 pipes, connects with the conduit 5 and extends downwardly; the lower end of said pipe is in communication with the inlet conduit 10 which communicates at one end 20 with the central passage of the shaft 4 and which is adapted to convey cooling air from 25 a fan or other fluid-forcing apparatus (not shown) into the shaft and, if desired, into the pipe 9, the latter preferably communicating 30 with the conduit 10 at a point located between the fan and the shaft. A branch pipe 11 establishes communication 35 between each pipe 9 and one or more of the roasting spaces, as for example, that of the 40 lowermost hearth into which the flues or conduits 7 also discharge. The transverse conduit 5 is provided with dampers *b* located 45 between the shaft 4 and the outlet 8 on the one hand and the bustle pipe 6 and 50 the pipe 9 on the other hand. Dampers *c* are provided between the transverse conduit 55 and the bustle pipe; dampers *d* and *e* are provided in the pipes 9 respectively above and below the point of communication between 60 said pipes and the branch pipes 11; and the branch pipes 11 are themselves provided with dampers *f*.

The device illustrated is adapted to be operated in a number of ways which will 40 depend upon the nature and qualities of the ore being roasted, which ores may be, for example, iron pyrites, copper pyrites, pyrrhotite, blende, galena or various mixtures thereof. According to each method of 45 operation, however, air, or other suitable cooling fluid, which has extracted a certain amount of heat from the furnace by being forced through the rotary stirring system and which has thus been raised to a tem- 50 perature which approaches the average tem- 55 perature of the various roasting spaces or zones is passed into heat exchanging proximity to all of the roasting zones of the furnace and then discharged into a relatively 60 cooler zone thereof, so as substantially to extract heat from the zones the temperatures of which are higher than said air tempera- 65 ture, thus causing the temperature of the various zones to approach the temperature of said air. In other words, the cooling air, after it has traversed the shaft and rabble arms of the rotary stirring system, 70 is caused to pass through the conduits 7 and

to extract heat from the hotter roasting spaces and add heat to the cooler roasting spaces, this heat exchange being practically accomplished in view of the fact that said conduits are made of material which conducts heat readily, said material being exposed to and in direct contact with the atmosphere of said roasting spaces; after being thus subjected to heat exchange, the air is conducted, as shown, into the lowermost 75 roasting space.

According to one method of operation, the dampers, *a*, *d*, and *f* are closed and the dampers *b* and *c* are open, the dampers *e* being either open or closed. Air is forced 80 by the fan through the conduit 10 and passes therefrom into and through the rabble arm system from which it issues into the transverse conduit 5 and passes therefrom successively into the bustle pipe 6 and heat 85 exchanging conduits 7, finally discharging into the lower hearth space. If desired, the damper *a* may be opened slightly and if necessary the dampers *b* and *c* be closed slightly so as to cause any controlled proportion 90 of the air to pass from the transverse conduit into the atmosphere through the stack 8, and the remainder to pass through the conduits 7 into the lowermost combustion chamber. Further heat control 95 may be had by opening the dampers *d* and *f* more or less and closing the damper *e*, the damper *a* being either open or closed, so that a portion of the air will pass down through the pipe 9 into the branch 11 and 100 discharge into the lower hearth space. It is obvious that a suitable manipulation of the dampers will result in causing all of the air to pass into the atmosphere through the exit 8, all of it to pass through the heat interchanging conduits 7 into the lower portions of the furnace, all of it to pass through the external pipe 9 into said lower portions, all of it to pass through any two of these 105 passages 7, 8 and 9, or any proportion of it to pass through these two or three passages. It will be seen that the furnace is very flexible in its operation and can be accommodated to the roasting of any kind of ore. It is further possible to manipulate the 110 dampers in an obvious manner so as to cause all of the cooling air to pass from the rotary mechanism through the exit stack while at the same time air is caused to flow directly from the conduit 10 into the pipe 9 and 115 from said pipe either directly into the lower chamber in non-heated condition or through the heat exchanging conduits 7 into said chamber, the air in the latter case being preheated before passing into said chamber 120 and serving to regulate and control the heat and temperature of the furnace by extracting heat from the upper portions of the furnace, which heat has been conducted from the chamber through the metal forming the 125 130

said conduits 7, and conveying such extracted heat into the lower portions of the furnace.

I claim:

- 5 1. In the art of roasting sulfur-bearing ores, the improvement, which comprises first heating air to a temperature which approaches the average temperature of the various roasting zones, then passing a volume of the heated air into heat exchanging proximity to all of the roasting zones, whereby heat is substantially extracted from zones the temperatures of which are higher than said air temperature and added to zones the temperatures of which are lower than said air temperature, thus causing the temperatures of the various zones to approach the temperature of said air, and finally introducing the air into a relatively cool roasting zone, substantially as and for the purpose described.
- 10 2. In the art of roasting sulfur-bearing ores, the improvement which comprises first heating air to a temperature which ap-
- 15
- 20

proaches the average temperature of the 25 roasting zones by passing said air into heat exchanging proximity to all of the said zones, then passing a controlled volume of the heated air into heat exchanging proximity to all of the roasting zones, whereby 30 heat is substantially extracted from zones the temperatures of which are higher than said air temperature and added to zones the temperatures of which are lower than said air temperature, thus causing the temperatures of the various zones to approach the 35 temperature of said air, and finally introducing the air into a relatively cool roasting zone, substantially as and for the purpose described.

In testimony whereof I have hereunto set my hand in the presence of two subscribing witnesses.

HARRY H. STOUT.
